PRESSER FOOT FOR SHOE STITCHING MACHINES

William C. Re, Glendale, N. Y.

Application December 4, 1929, Serial No. 411,404

3 Claims. (Cl. 112—60)

This invention relates to machines for operating on shoes and the like, the invention being more particularly related to an improved presser foot device for use in connection with shoe stitching machines.

The device of the present invention is illustrated as associated with the mechanism of the Goodyear stitching machine of the kind now in general use.

The invention has for an object the provision of an improved construction of the above character, one capable of performing its work in an effective and expeditious manner, and one which will obviate some of the objections at present prevailing in the types of devices employed in operating on stitched down shoes.

More particularly, the invention has in view the provision of a device of the character referred to and in a manner as hereinafter described, by which effectively to accomplish the following purposes:—(1) to provide a device in the nature of an attachment, adapted readily and conveniently to be applied to the well-known type of stitching machines as referred to; (2) to provide a device capable of functioning as a stitch and sole leveler; (3) to provide a device having the function of an anvil-like guard to aid the operator in maintaining the sole on the table of the machine in a practically true relative horizontal position which is important and desirable in better class work; and (4) to provide a device whereby to press back into the sole any ends or portions of wire staples which at times are pushed up through the sole by the awl of the stitching machine.

It may be remarked that as now stitched with the old presser foot, shoes are frequently found to have the ends of the wire staples protruding from the bottom of the sole. Such protruding ends frequently tear or cut the fingers of the operators. With my improved presser foot, the shoe is leveled and the projecting ends of the wire staples are embedded in the sole at a single operation in connection with the stitching.

The presser foot of the present invention may take various forms, the preferred embodiment comprising a unitary structure composed of a perforated plate adapted to be secured to the usual presser foot lever, there being a lateral bar extending from the perforated plate and carrying an outwardly and forwardly extending presser part or foot adapted normally to project over and beyond the usual stitching table of the machine.

According to another novel and convenient embodiment, the perforated plate, lateral bar and presser bar or foot may be produced as two hinge

connected parts, with the provision of spring means for forcing the bar or foot into strong yielding contact with the sole of the shoe when stitching.

According to a further novel and convenient embodiment, the perforated plate and lateral bar are produced as a one-piece structure, and to the end of the bar is applied a forwardly extending pin carrying a sleeve roller. Besides these specifically enumerated features, the invention involves other features of advantage which will be apparent to those skilled in the shoe-making art, and it will be understood that I do not limit myself to the exact configuration and arrangement herein disclosed, since in practice I may resort to many alterations and refinements in carrying out the invention.

Other objects and advantages of the invention will appear hereinafter.

The invention resides in the improved presser foot and leveler and in the form, construction and relative arrangement or arrangements of its parts, as will be hereinafter more fully described, illustrated in the accompanying drawing and subsequently incorporated in the subjoined claims.

Several simple and practical embodiments of the invention are illustrated in the accompanying drawing, which forms a material part of this application, and in which:

Figure 1 represents a fragmentary perspective view showing my improved presser foot as it appears when attached to the presser foot lever of a Goodyear stitching machine and in position for service;

Fig. 2 represents a side elevational view of the presser foot with a portion of a shoe in cross section as is also the stitching table of the machine, all in operative position;

Fig. 3 represents a detailed front elevational view of the improved presser foot;

Figs. 4 and 5 represent front and top views, respectively, of a modified form of the improved presser foot, showing a two-part construction with a spring; and

Figs. 6 and 7 represent front and top views, respectively, of another modified form of the improved presser foot in which a roller is employed.

Referring with more particularity to the accompanying drawing, and first to the parts shown in Figs. 1 and 2, 10 designates a presser foot lever of the kind customarily used on a Goodyear stitching machine (for example, the Goodyear outsole rapid lock stitch machine, Model O, catalogue published June 11, 1927), while 11 designates a

nates the usual gauge or supporting table having therein the usual longitudinal slot 12 for the accommodation of the awl 13 and needle 14 during the stitching operations.

5 An embodiment of the improved presser foot of this invention is indicated generically by the numeral 16 and is illustrated as comprising a plate or portion 17 having threaded perforations 18 adapted to receive suitable screw bolts 19 where-
10 by to be secured as shown to the lever 10 of the machine. Extending laterally from the plate 17 is an integral bar 20 which is furnished at its outer end with an outwardly or forwardly projecting presser foot and leveler 21. The parts of
15 the device are so fashioned and arranged that when the plate 17 is secured to the lever 10, the bar 20 and the presser foot and leveler 21 will be positioned above the table 11, with the bar extending in a direction longitudinally of the table
20 adjacent one side of the vertical plane in which the slot 12 lies and so as not to interfere with the usual movements of the awl and needle through the slot, while the presser foot and leveler extends in a direction transversely of the table in a
25 transverse vertical plane adjacent the rear end of the slot where it will not interfere with the movements of the awl and needle and where it will act upon the stitches 21a exposed at the underside of the sole 21b. It will be appreciated that as
30 the lever 10 vibrates rapidly up and down, the device of my invention will vibrate with it so that the exposed portions of the stitches will be hammered into the sole and made substantially even or level with the surface thereof. It is well known that
35 the number of stitches produced in the sole is usually from eight to ten to the inch, and also that during the sewing operation the upward awl thrusts tend to move the sole upwardly from the table. The width of the underneath striking or
40 contacting face of the part 21 is equal to or greater than the combined length of a number of stitches (for instance, four or five stitches) and under the rapid vibrating action, the exposed portions of several stitches are at one time pressed
45 or hammered under each impact, so that under the usual stitching movement of the sole which is relatively slow in comparison with the rapid vibrating action of the leveler the exposed portion of each stitch over the full length thereof will be repeatedly subjected to the hammering impact.
50 Operating against the hammering impact exerted downwardly is an upwardly exerted impact produced by the thrusts of the awl, so that the stitches are always substantially in contact with the part 21 and under the two forces operating against each other from opposite directions. This results in completely leveling the stitching as well as any of the material of the sole displaced upwardly as a result of the thrusts of the awl.
55 In Fig. 2, I illustrate the sole of a shoe inter-
60 posed for the sewing operation between the table and the device of my invention. The shoe fractionally shown at a is of course held in inverted position in the usual way, with the marginal side portion a' of the sole structure adjacent the upper
65 a'' superposed upon the table 11. The bar 20 and the presser foot and leveler 21 operate upon the underside of the outer sole 21b which, of course, is presented face upward since the shoe is inverted.
70 The bar 20 operates upon the marginal portion of the sole lengthwise thereof and at the outer side of the paths of the awl and needle working
75 through the slot. The presser foot and leveler 21

operates upon the sole across the line of stitching adjacent the rear end of the elongated slot 12.

The presser foot lever 10 is operated automatically by the sewing machine, being vibrated up and down in the usual way, and with the result that the parts 20 and 21 are vibrated in their respective positions upon the underside of the sole. This vibration is necessary in order to allow the feeding movement of the shoe for sewing the sole all around its marginal edge. The vibrating parts 20 and 21 hold the sole to the table against upward movement under the thrusts of the awl. In cooperation with the table 11, the parts 20 and 21 tend to maintain the shoe in horizontal position. Said angularly related parts 20 and 21 serve in the capacity of anvil-like guards for the sole so as to prevent upward movement thereof under the upward thrusts of the awl through the sole structure; and in addition to this function they tend to maintain the sole operatively in place so as to prevent the breaking of the needles.

With the aid of said parts 20 and 21 in the arrangement shown, the operator can readily present and maintain the sole of the shoe in the desired horizontal position where the stitching will be accomplished with accuracy, neatness and dispatch. The device also serves as a stitch and sole leveler. In use, as shown in Fig. 2, the presser foot 21 extends inwardly of the sole well beyond the stitches 21a which are exposed at the underside of the sole 21b along the marginal edge thereof. As the stitching proceeds, the presser foot operates upon the sole so as to have a leveling action thereon and as well upon the exposed stitches which are leveled in conformity with the underside of the sole. The presser foot 21 should be of a cross sectional dimension sufficient to operate upon at least two stitches at one time. In this connection, it may be remarked that if the ends of any wire staples protrude from the underside of the sole along the marginal edge thereof in the zone of the stitching, such protruding ends will be engaged by the presser foot 21 and pressed back into the sole so as to be embedded therein.

In Figs. 4 and 5 of the drawing, a two-piece presser foot is disclosed, in which the plate portion 17 is made with spaced apart ears 22 carrying a cross pin 22'. Arranged upon the pin 22' so as to have relative swinging movement thereon and between the ears 22 is the head end 23 of a bar 24 carrying the outwardly or forwardly projecting presser bar or foot 25. Coiled about the pin 22' between the head 23 and one of the ears 22 is a strong spring 26 which places the arm 24 under tension, yieldingly maintaining it and consequently the presser bar or foot 25, at the lower terminal of movement for operating upon the shoe. By this arrangement, the spring 26 yieldingly maintains the bar 25 in contact with the sole of the shoe when stitching. In the employment of said spring, the ears 22 operate as a base point on the underside of the sole, and the parts 24 and 25 possess the advantage of yielding relatively to said base point so as to follow more closely the configuration of the sole under the spring urge.

In the embodiment of the invention shown in Figs. 6 and 7, the plate 17 and bar 20 are represented as produced in one piece, and in the outer end of the bar 20 is secured one end of an outwardly or forwardly projecting pin 27. A roller or sleeve 28 is mounted on the pin 27 to turn thereon and serve as the presser foot and leveler. The devices 25 (Figs. 4 and 5) and 28 (Figs. 6 and 7) being of cylindrical form and ex- 75

tending in their axial direction across the line of stitches, naturally hammer on the stitches along transverse lines or bars of impact, and this action is of course accompanied by additional lines or bars of impact induced by the force moving from the opposite direction and consisting of the effective tendency of the sole to have upward impact against the leveling device under the upward thrusts of the awl.

10 From the foregoing it will be evident that I have produced a simple, practical and inexpensive presser foot and leveler attachment, and one which will effectively perform the several functions enumerated in the statement of objects and 15 in the foregoing description. It is to be understood that the terms and expressions employed herein are intended as descriptive only, and in no sense are they to be construed as limitations as regards mechanical equivalents. While I have 20 shown and described several embodiments of my invention, it is to be understood that the same are susceptible of modification in various particulars without departing from the spirit or scope of the invention or sacrificing any of its 25 advantages.

I claim:

1. A presser foot attachment for shoe-stitching machines including a table with an awl and needle slot, said attachment comprising an element for connection with the presser foot lever of the machine, characterized by the combination of two angularly arranged parts adapted to cooperate with the table on which the shoe is stitched and the awl and needle slot of such table, one of said parts consisting of an elongated bar pivotally united at one end to the supporting element and positioned longitudinally of the table and slot to serve as an anvil-like shield preventing upward displacement of the sole under the thrust of the awl during the stitching operation, the second part consisting of a leveler device for acting upon the sole across the line of formed stitches and in such relation to the slot that it will be clear of the path of the awl and needle passing through the slot, and spring means acting on the bar and yieldable to permit relative movement thereof when the leveler

device acts with sufficient force upon the stitches and sole.

2. In combination with a shoe-stitching machine including a table with an awl and needle slot, presser mechanism including a bar extending longitudinally of the table in a position at one side of the vertical plane of the slot, a pin projecting angularly from the bar above the table, and a roller on said pin adapted to turn upon the sole of a shoe rested in inverted position upon the table over the slot, said bar being positioned to act upon the sole at the outerside of the paths of the awl and needle working through the slot, and said pin and roller being so positioned that the roller will clear the path of the awl and 15 needle working through the slot while the roller will level the stitches produced by the needle.

3. A stitch leveling attachment for a shoe sole stitching machine of the class producing raised stitches on the bottom of the sole, the machine 20 having a vibrating presser foot lever and a table with an awl and needle slot, said attachment comprising an element attached to and vibrating with said lever, characterized by the combination of two angularly related parts adapted to 25 cooperate with the table on which the shoe sole is stitched and the awl and needle slot in such table, one of said parts consisting of an elongated bar extending in the direction of its length longitudinally of the table and slot to operate 30 as a top anvil-like shield for the sole whereby to limit upward displacement of the sole under the upward thrust of the awl during the stitching operation, and the other of said parts consisting of a straight leveler device joined at one 35 end at right angles to said bar and extending in the direction of its length transversely of the table and slot entirely across and beyond the line of raised stitches to act directly upon and across the same and upon the sole at either side 40 of the raised stitches so as to flatten and level the raised stitches, while leaving them exposed, upon and to the level of the sole during the operation of the presser foot lever, the inner surface of said element being defined solely by the inner 45 surfaces of said angularly related parts.

WILLIAM C. RE.
